UNITED STATES PATENT OFFICE.

MARLON H. WINSLOW, OF TERRE HAUTE, INDIANA.

RAILROAD SCALE.

Application filed October 17, 1924. Serial No. 744,141.

This invention is a railroad scale primarily. One feature of the invention consists in arranging the intermediate bearings for carrying the load on the cross beams vertically below the railway rails so that the load will be directly over the bearing, and in order to lengthen the cross levers as much as possible to obtain better leverage, they are arranged obliquely to the intermediate lever, instead of as at right angles as heretofore, and are carried on said beam by angularly adjustable bearing blocks or plates rendering such angular arrangement of levers practical. This enables said cross levers to receive the load at a point immediately below the railway rails and to transmit the load to the intermediate lever without reducing the length thereof and with a great length thereof as possible.

Another feature of the invention consists in a compound bearing block consisting of upper and lower bearing plates and intermediate insertable plates, whereby the vertical thickness of the bearing block construction may be altered or adjusted.

Another feature of the invention consists in mounting the transmitting end of the intermediate lever on another transmitting lever by means of a bearing construction having two bearing plates at right angles to each other and rollers between said bearing plates parallel with one of said bearing blocks, preferably the one receiving the transmitting end of the intermediate lever, whereby the changes in said levers due to expansion or contraction or any other cause will be taken up by said bearing construction.

The full nature of the invention will be understood from the accompanying drawings and the following description and claims.

In the drawings, Figure 1 is a central vertical section through a railway track and load supporting beams, with an end elevation of the leverage or scale construction, parts being omitted. Fig. 2 is a plan view of a portion of the scale mechanism shown in Fig. 1. Fig. 3 is a side elevation of a compound bearing block for the transmitting end of the cross levers. Fig. 4 is a plan view of what is shown in Fig. 3. Fig. 5 is a vertical transverse section of the bearing construction for the transmitting end of the intermediate lever.

In the drawings, there is shown herein railway rails 10 of a railway track on stands 11 carried by cross beams 12 which in turn are carried by the I-beams 13 immediately under the railway rails.

Below said railway construction the scale construction is mounted, a part or one end of which is herein shown. It consists of a pair of transverse levers 15 receiving the load from the railway rails, an intermediate lever 16 transmitting the load from the levers 15 to the lever 17 which transmits the load to the weight-indicating mechanism, not shown.

In the full scale apparatus, which is not here shown, there is a set of cross levers 15 and the longitudinal levers 16 at each end of the scale, and on each side of the lever 17.

Each cross beam is fulcrumed at its outer end on a stand 20 and receives a load intermediate its length, in this construction, by a bearing 21, vertically under the railway rail. In said bearing there is a load block 22 on which the beam 13 rests. One feature of this invention consists in mounting the bearings 21 for the cross levers vertically under the railway rail as is very desirable. One difficulty about this mounting is that if the cross levers 15 are at a right angle to the intermediate lever, the levers 15 are too short, for the distance between the railway rails is fixed. This difficulty is overcome herein by lengthening the cross levers 15 or, at least, making them the same length as heretofore, but mounting them obliquely to the railway rails and to the lever 17, as indicated in Figs. 2 and 3. Hence, the knife edge bearings 21 on the cross lever 15 that support the load block 22 are at an angle not directly transverse to the lever 15. That is, the knife edges 21 are parallel with the railway rails, but not directly transverse of the cross levers which are oblique to the railway rails instead of at a right angle thereto. Likewise at the transmitting end of each cross lever there is a change in the bearing construction.

The knife edges 25 extend transversely across the cross levers 15 and rests in a bearing groove 26 on a bearing plate 27. This bearing groove 26 may be a hardened bearing insert or not, as desired. The bearing plate 27 rests upon another bearing plate 28 with intermediate filling plates 29 and the

lower bearing plate 27 has a bearing groove 30 in it that rests on a knife edge 31 on the intermediate lever 16. The bearing grooves or surfaces 26 and 30 are not at right angles to each other. The lower bearing surface 30 is at right angles to the intermediate lever 16, whereas the upper bearing surface 26 is perpendicular to the cross levers 15 and the railway rails and extends transversely of the cross lever to receive the knife edge 25 thereof. The bearing plates 27 and 28 are angularly adjustable so as to enable one of them to suit cross levers 15 of varying lengths, and they are held together by three lugs 32 on the upper plate 27 which overlap the edges of the filling plates 29 and lower plate 28. The bearing plates 29 are for the purpose of increasing the thickness of the double bearing block construction just described by inserting or removing one or more of said plates and they are held in position by the lugs 32.

The intermediate lever 16 is fulcrumed on the bearing block 35 near its load receiving end and at its load transmitting end there is a bearing construction between it and the lever 17, which is illustrated in Fig. 5. The load transmitting end of the intermediate lever 16 rests upon a bearing surface 36 of the bearing block 37 that is supported by a roller 38 transversely of said block and the beam 16. These rollers are supported in a bearing block 39 below that has a bearing surface 40 extending at right angles to the bearing surface 36 of the block above and transversely of the load transmitting beam 17. The adjacent faces of the blocks 37 and 39 are correspondingly grooved for holding the roller 38, but they are widened grooves and the purpose of this bearing construction is to adapt it for constant service regardless of the expansion and contraction of the levers 16 and 17 or any minor change in their relation from any cause.

45 The invention claimed is:

1. The combination with a pair of levers of a weighing scale, of a bearing construction between them which consists of upper and lower bearing plates angularly adjustable with relation to each other.

50 2. A weighing scale having the construction described in claim 1, with a plurality of lugs on one of said bearing plates peripherally engaging the other bearing plate.

55 3. A weighing scale including a pair of levers, a bearing construction between said levers having upper and lower plates with bearing surfaces thereon, and removable filling plates for varying the vertical thickness of the bearing construction.

60 4. A weighing scale including the con-

struction described in claim 3, and lugs secured to one of said bearing plates and overlapping the margins of the other bearing plate and the filling plate between said bearing plates. 65

5. The combination with a railway track having railway rails for carrying a load, of a weighing scale beneath the same having cross levers fulcrumed at their outer ends 70 and extending toward each other obliquely to the railway rails, bearings on the cross levers between their ends for receiving the load from the railway rails, which bearings are vertically below the railway rails, an intermediate lever parallel with the railway rails for receiving a load from the two cross levers, and angularly adjustable bearings between said cross levers and intermediate lever which are attachable to cross levers 80 of varying lengths and in various angular relationships to the intermediate lever due to the load receiving bearing being in vertical alignment with the railway rail.

6. A weighing scale having two levers, 85 whereby the load is transmitted from one lever to the other, and a bearing construction between said levers having upper and lower bearing plates arranged to be angularly adjustable with relation to each other 90 to render the same serviceable regardless of the minor changes in the relation between said levers.

7. A weighing scale having two levers, whereby the load is transmitted from one 95 lever to the other, a bearing construction between said levers consisting of an upper bearing plate, a lower bearing plate, and intermediate rollers, said bearing plates being grooved to receive said rollers and the 100 grooves being wider than the rollers, substantially as set forth.

8. The combination with a pair of levers of a weighing scale, one of which levers transmits the load to the other lever, of a 105 bearing construction between the adjacent parts of said levers consisting of a round upper bearing plate for one lever, a round lower bearing plate for the other lever, and intermediate rollers between said bearing 110 plates.

9. A weighing scale including a pair of oppositely extending load-receiving cross levers, an intermediate lever to receive the load from the cross levers, said cross levers 115 extending obliquely of said intermediate lever, and a round bearing construction under the inner end of each cross lever and carried by said intermediate lever.

In witness whereof, I have hereunto affixed my signature.

MARLON H. WINSLOW.
